DESIGN FOR A HUMIDIFIER CONTAINER

John Krapf and George Krapf, Milwaukee, Wis.

Application September 22, 1938, Serial No. 80,035

Term of patent 14 years

To all whom it may concern:

Be it known that we, John and George Krapf, both citizens of the United States, of Milwaukee, in the county of Milwaukee and State of Wisconsin, have invented a new, original, and ornamental Design for a Humidifier Container, of which the following is a specification, reference being had to the accompanying drawing, forming part thereof.

In the drawing:

We claim:

The ornamental design for a humidifier container, as shown.

JOHN KRAPF.
GEORGE KRAPF.
